UNITED STATES PATENT OFFICE

115,765

DESIGN FOR A COMBINED EARMUFF DISPLAY AND STAND THEREFOR

Charles L. Osborn, Chicago, Ill.

Application January 11, 1939, Serial No. 82,299

Term of patent 3½ years

To all whom it may concern:

Be it known that I, Charles L. Osborn, a citizen of the United States and a resident of Chicago, in the county of Cook and State of Illinois, have invented a new, original, and ornamental Design for a Combined Earmuff Display and Stand Therefor, of which the following is a specification, reference being had to the accompanying drawing, forming a part thereof.

Fig. 1 is a front elevational view of a combined earmuff display and stand therefor, showing my design; and

Fig. 2 is a side elevational view thereof.

I claim:

The ornamental design for a combined earmuff display and stand therefor, as shown.

CHARLES L. OSBORN.
